(57) **CLAIM**

We claim, the ornamental design for a luminaire, as shown and described.

DESCRIPTION

FIG. 1 is a top perspective view of a third embodiment of the invention;

FIG. 2 is a bottom perspective view of the embodiment of FIG. 1;

FIG. 3 is a side plan view of the embodiment of FIG. 1, with the opposite side being a mirror image thereof;

FIG. 4 is a front elevation view of the embodiment of FIG. 1, with the opposite side being a mirror image thereof;

FIG. 5 is a top plan view of the embodiment of FIG. 1; and, FIG. 6 is a bottom plan view of the embodiment of FIG. 1. The degree of transparency or translucency of the lens of the luminaire forms no part of the claimed design.

The dash-dot and the dash-dot lines shown in the drawings illustrate unclaimed environmental structures and form no part of the claimed design.

References to “side”, “top”, “front”, “rear” and “reverse” in the figure descriptions are not meant to require certain in-use orientation.
